(57) CLAIM

The ornamental design for a folding table, as shown and described.

DESCRIPTION

FIG. 1 is a perspective view of a short version of the folding table, including legs, of this design, with the legs shown in an unfolded, open position.

FIG. 2 is a top view of the embodiment depicted in **FIG. 1**.

FIG. 3 is a front elevational view of the embodiment depicted in **FIG. 1**.

FIG. 4 is a bottom view of the embodiment depicted in **FIG. 1**.

FIG. 5 is a back elevational view of the embodiment depicted in **FIG. 1**.

FIG. 6 is a side elevational view of the embodiment depicted in **FIG. 1**, taken from the right side.

FIG. 7 is a side elevational view of the embodiment depicted in **FIG. 1**, taken from the left side.

FIG. 8 is a bottom view of the embodiment depicted in **FIG. 1**, with the legs shown in a folded, closed position.

FIG. 9 is a perspective view of a long version of the folding table, including legs, of this design, with the legs shown in an unfolded, open position.

FIG. 10 is a top view of the embodiment depicted in **FIG. 9**.

FIG. 11 is a front elevational view of the embodiment depicted in **FIG. 9**.

FIG. 12 is a bottom view of the embodiment depicted in **FIG. 9**.

FIG. 13 is a back elevational view of the embodiment depicted in **FIG. 9**.

FIG. 14 is a side elevational view of the embodiment depicted in **FIG. 9**, taken from the right side.

FIG. 15 is a side elevational view of the embodiment depicted in **FIG. 9**, taken from the left side; and,

FIG. 16 is a bottom view of the embodiment depicted in **FIG. 9**, with the legs shown in a folded, closed position.
